TYPEWRITING MACHINE

Jesse A. B. Smith, Stamford, Conn., assignor to
Underwood Elliott Fisher Company, New
York, N. Y., a corporation of Delaware

Original application November 15, 1933, Serial
No. 698,063. Divided and this application
March 14, 1938, Serial No. 195,717

7 Claims. (Cl. 197—102)

This invention relates to keys for typewriters and similar machines.

It is the general object of this invention to provide a key of simple construction and fabricated of parts adapted for economic manufacture, the key affording a comfortable touch for the operator.

One of the features of the present invention is embodied in the novel structure of same which, although comprising a character-disk formed of normally flat material, presents a striking surface of concave yieldable structure to assure an easy touch in use by conforming substantially to the finger tips of the operator.

In accordance with the invention, the key may comprise a cup or base member adapted for attachment to the key-lever stems of a typewriter, the cup providing an upstanding rim within which a ring is disposed, and having a normally flat character-disk assembled into the key so that the same is supported at its periphery or marginal portions only, by the ring or other suitable means. A cap having an inturned downwardly directed brim is placed over the cup and securely fastened thereto as by lugs bent over the cup after assembly. During assembly, the inner edge or lip of the inturned cap-brim engages the character-disk along an annular line somewhat within the periphery of the disk and, as the cap is pressed into place, the brim thereof causes the normally flat disk to assume a concave or depressed formation, in that the periphery of the disk is supported by the mentioned ring. The cap is pressed downwardly until the disk and ring are securely gripped and the disk has the desired concavity, in which position the cap is fixed to secure the assembly of the key.

Other features and advantages will herein-after appear.

This is a division of my co-pending application Serial No. 55,503, filed December 21, 1935. During the pendency of my application Serial No. 698,063, filed November 15, 1933, (now Patent No. 2,059,615), division was required of certain of the subject matter therein. This subject matter was incorporated in my co-pending application Serial No. 55,503. Further division having been required, said subject matter is now presented in the present application.

In the accompanying drawing:

Figure 1 is a perspective view of the assembled key.

Figure 2 is a vertical sectional view of the key, and,

Figure 3 is an exploded view of the key parts shown in perspective.

Referring now to the drawing for a more detailed description thereof, the numeral 5 indicates the usual key-lever stem of a typewriter upon which is affixed a key-cup 6 having a flat socket 7 fitting over the stem 5. The key-cup 6 includes a bottom wall 8 and a side wall or rim 9. A character-disk 10 is provided, the same being preferably formed of two layers, the lower layer 10 of an opaque, flexible material having a type-character thereon, the upper layer being of transparent, relatively hard flexible material overlying, and preferably affixed to the lower layer to provide a protective coating for the type-character so as to resist scratching or otherwise marring same. The character-disk 10 is normally flat, as shown in Figure 3 and, being flexible, may be bent or flexed into a concave or dished formation by means hereinafter described, as 20 shown in Figure 2.

A ring 11 rests in the cup 6 and preferably fits snugly against the rim 9 thereof, and the character-disk 10 rests on the ring 11, being in contact therewith only adjacent the periphery of the disk 10. The combined thickness of the ring 11 and the composite disk 10 may approximate the depth of the cup 6 as defined by the height of the rim 9 thereof. A cap 12 is provided, the same being adapted to telescope over the rim 9 of the cup 6 and has a series of bendable lugs 13 thereon. The cap 12 also includes an inturned, downwardly sloping brim 14 of an internal diameter somewhat less than the ring 11.

In assembling, the ring 11 and the character-disk 10 are placed within the cup 6, the disk 10 being in its normally flat condition. The cap 12 is placed over the cup 6, the lugs 13 thereof being straight as shown in Figure 3. As the cap 12 is initially pressed into place, the inner edge of the brim 14 engages the disk 10 at an annular line substantially within the ring 11, and the normally flat disk 10 is thereby pressed into a tensioned concave shape, the ring 11 co-acting with the downwardly sloping brim 14 by supporting the disk at its periphery while the brim 14 presses at a medial area of the disk. It is to be noted here that the ring 11 is preferably round in cross section so as to augment the flexing effect of the brim 14 on the disk 10, in that the round section of the ring assures only a line contact and permits a slight rolling action of the disk 10 as same is flexed into a concave form. The final position of the cap 12 may be determined by the brim 14 55

thereof abutting the edge of the cup-rim 9, at which position the cap-lugs 13 are bent or clinched under the bottom wall 8 of the cup 6. It is desired, however, that the proportions of the 5 respective parts, particularly the thickness of the disk 10 and ring 11 with reference to the depth of the cup-rim 9, be such as to assure a positive clamping of the disk 10 in place so as to prevent rotation thereof to obviate derangement of the 10 type-character from normal reading position. In this regard, it is preferred that the ring 11 be made of a relatively non-yielding material to assure the desired gripping or clamping of the disk 10, although the ring 11 may be yieldable slightly 15 so as to compensate for inequalities in the relative sizes of the materials.

From the foregoing it will be seen that there is provided a novel structure for the keys of a typewriter, the same comprising a cup adapted 20 for mounting on a typewriter key-lever, means carried by the cup for supporting a character-disk adjacent its periphery only, and a cap af- 25 fixed to the cup and having an inturned downwardly directed brim arranged to engage the normally flat disk in a manner to hold same in concave form, co-actively with the means by which the disk is supported adjacent its periphery. The disk, being fabricated of a normally flat sheet material, may be more economically manufac- 30 tured and, nevertheless in the finished key, af- fords a comfortable yielding touch for the fingers of the operator, in its concave or dished form. The downward sloping of the cap-brim, which 35 sloping may substantially conform to the con- cavity of the disk, further assures a comfortable, adequately-sized finger-engaging surface of the assembled key, the thickness of the cap-brim be- 40 ing so slight as to be imperceptible to the touch.

What is claimed as new is:

40 1. A key for use with a typewriter or the like, comprising in combination, a member adapted for mounting on a key-lever, a normally flat disk, means carried by said member for supporting said disk adjacent its periphery only, and a cap se- 45 cured to said member and having an inturned down- 50 wardly directed brim overlying said supporting means and engaging said disk at marginal portions substantially within the periphery of said disk and co-acting with said supporting means to hold said disk in tensioned concave forma- 55 tion.

55 2. A key for use with a typewriter or the like, comprising in combination, a cup adapted for mounting on a key-lever, a normally flat disk, means carried by said cup for supporting said disk adjacent its periphery only, and a cap se- 60 cured to said cup and having an inturned down- 65 wardly directed brim overlying said supporting means and engaging said disk at marginal portions substantially within the periphery of said disk and co-acting with said supporting means to hold said disk in tensioned concave forma- 70 tion.

3. A key for use with a typewriter or the like, comprising in combination, a cup adapted for mounting on a key-lever, a ring lying within said cup, a normally flat disk resting adjacent its periphery only upon said ring, and a cap secured to said cup and having an inturned downwardly directed brim engaging said disk at marginal portions substantially within said ring and co-acting with said ring to hold said disk in tensioned concave formation. 5

4. A key for use with a typewriter or the like, comprising in combination, a cup adapted for mounting on a key-lever and having an upstanding rim, a ring lying within said cup-rim, a normally flat disk resting adjacent its periphery only upon said ring and lying within said cup and a cap secured to said cup having an inturned downwardly directed brim overlying said disk and said ring to engage portions of said disk inwardly beyond said ring and co-act with said ring to hold 10 said disk in tensioned concave formation. 20

5. A key for use with a typewriter or the like, comprising in combination, a cup having an up- 25 standing rim and adapted for mounting on a key- lever, a ring of round material lying within said cup, a normally flat disk having line contact ad- 30 jacent its periphery, with said ring, and a cap secured to said cup and having an inturned down- 35 wardly directed brim engaging said disk at marginal portions substantially within the line of contact with said ring and co-acting with said ring to hold said disk in tensioned concave forma- 40 tion. 50

6. A key for use with a typewriter or the like, comprising in combination, a cup having an up- 35 standing rim and adapted for mounting on a key- lever, a ring lying within said cup, a normally flat disk resting upon said ring adjacent its periphery only and lying within said cup, and a cap 45 secured to said cup and having an inturned down- 50 wardly directed brim abutting the edge of said cup-rim and overlying same to engage marginal portions of said disk substantially within said ring and co-acting with said ring to hold 55 said disk in tensioned concave formation. 60

7. A key for use with a typewriter or the like, comprising in combination, a cup having an up- 55 standing rim and adapted for mounting on a key- lever, a ring lying within said cup, a normally flat character-disk resting upon said ring ad- 60 jacent its periphery only and lying within said cup, and a cap having an inturned downwardly 65 directed brim engaging the edge of said cup-rim, and projecting within the cup to overlie said ring and engage said disk at marginal portions in- 70 teriorly of said ring so as to co-act with said ring in holding said disk in tensioned concave forma- 75 tion, said cap-brim clamping said disk non-ro- 80 tatively against said ring. 85
